UNITED STATES PATENT OFFICE.

JOSEPH PERELES, OF MILWAUKEE, WISCONSIN.

DESIGN FOR A SODA FOUNTAIN FRUIT SQUEEZING APPLIANCE.

Application filed September 15, 1928. Serial No. 28,148. Term of patent 14 years.

To all whom it may concern:

Be it known that I, JOSEPH PERELES, a citizen of the United States, residing at Milwaukee, in the county of Milwaukee and State of Wisconsin, have invented a new, original, and ornamental Design for Soda Fountain Fruit Squeezing Appliance, of which the following is a specification, reference being had to the accompanying drawing, forming part thereof.

The drawing is an isometric perspective view of a soda fountain fruit squeezing appliance showing my new design.

I claim:

The ornamental design for a soda fountain fruit squeezing appliance as shown.

JOSEPH PERELES.
